UNITED STATES PATENT OFFICE.

LOUIS SOLOMON, OF NEW YORK, N. Y., ASSIGNOR OF ONE-FOURTH TO DAVID D. GLANZ, OF NEW YORK, N. Y.

LOCK.

Application filed December 30, 1925. Serial No. 78,307.

The object of my invention is the provision of a key-less lock adapted to various closure purposes, and especially for use in conjunction with doors for houses, apartments, etc., where special precaution against surreptitious entrance is a desideratum; and it consists, substantially, in the specific combination and arrangement of devices and component parts herein described and claimed, whereby the lock may be set to open from the exterior only by a prescribed selective number of push-buttons, and incidentally an alarm given in case of tampering by those unfamiliar with the requirements, all as hereinafter fully set forth.

In the accompanying drawings I illustrate a practical embodiment of the essential features of my invention as incorporated in a keyless lock designed more particularly for use on doors, although I do not limit myself in this respect, nor to the identical construction and arrangement of parts and appurtenances shown by way of exemplification, since changes may be made in minor details, and equivalent mechanical expedients resorted to, with like results, and without departing from the spirit and intent of my invention.

With this understanding:—

30 Fig. 1, represents an elevation of a portion of the outer side of a door provided with my keyless plural press button lock;

Fig. 2, is an elevation of the casing and interior of the lock as removed from the door and base plate, and taken upon plane of line 2—2, Fig. 4;

Fig. 3, is an elevation of the inner face of the base plate, taken upon plane of line 3—3, Fig. 4;

40 Fig. 4, is a transverse section taken upon plane of line 4—4, Fig. 2, showing the door handle spindle as held against rotation;

Fig. 5, is a like transverse section showing the door handle spindle released;

45 Fig. 6, is a central longitudinal sectional elevation of the combination control cylinder and adjacent parts of the lock mechanism and casing;

Fig. 7, is a sectional detail taken upon plane of line 7—7, Fig. 6;

Fig. 8, is a sectional detail, upon an enlarged scale, taken upon plane of line 8—8, Fig. 6, and illustrating the tripping of the electric alarm circuit closer;

55 Fig. 9, is a sectional detail, upon an en-

larged scale, taken upon plane of line 9—9, Fig. 3;

Fig. 10, is a sectional detail, also upon an enlarged scale, taken upon plane of line 10—10, Fig. 3;

Fig. 11, is an elevation of the peripheral surface of the combination control cylinder as projected on the flat, to better show the correlation of the trip holes and their cover slides;

Fig. 12, is a transverse vertical sectional elevation taken upon plane of line 12—12, Figs. 1 and 2;

Fig. 13, is a similar view taken upon plane of line 13—13, Figs. 1 and 2;

Fig. 14, is a sectional detail, upon an enlarged scale, showing the means for effecting the adjustment of the latch trip on the combination control cylinder;

Fig. 15, is a sectional detail showing the means of attachment of the base plate of the casing to the main or box portion thereof;

Fig. 16, is a sectional detail showing the mounting of the interior push rod for effecting the release of the bolt latch lever.

The type of lock shown is attached to the inner side of a door D, by means of screws S, S, extending through the front plate C, and rear plate C', of the casing, as indicated more particularly in Figs. 4 and 5, of the drawings. The main portion C, of the casing consists of a rectangular box C, formed with a bottom c, and end flanges c', c'', to which latter is attached a top or cover plate C'', as by means of screws s', s'', Figs. 2 and 6,—the aforesaid back plate C', being secured to the main or box portion of the casing C, by screws s'', s'', as shown more particularly in Fig. 15, of the drawings.

B, is a reciprocating bolt mounted between parallel guiding and supporting flanges c'', c'', on the inner side of the box casing C, and shot in either direction by a thrust arm h, engaging with the sides of a recess b, formed for the purpose in the rear extremity of the bolt B, as shown in Fig. 2, said thrust arm being rigidly attached to handle spindle H, and the latter being provided at either extremity with the usual handle knobs h', h'', as shown more particularly in Fig. 4, of the drawing. Also rigidly attached to the handle spindle H, adjacent to the thrust arm h, and extending at right angles thereto, is a detent arm 110

h^4 , for engagement with the shoulder l , of a spring latch lever L , fulcrumed between lugs c^4 , c^4 , on the bottom plate c , of the box casing C . A spring l' , bearing against the rear side of said latch lever L , tends constantly to hold the latter in engagement with said detent arm h^4 , when the bolt B , is advanced as in Fig. 2, of the drawings, thereby preventing retractile movement of 10 said bolt under normal conditions.

Obviously the rocking back of the spring latch lever L , from engagement with the detent arm h^4 , will admit of the turning of the handle spindle H , and the retraction of 15 the bolt B , by means of the thrust arm h , and this may be accomplished from the exterior side of the door through the medium of a prescribed manipulation of the plural push button mechanism hereinafter described, or from the inner side of the door 20 D , by means of a single independent push rod i , shown in detail in Fig. 16, of the drawings.

Thus while the door is practically impregnable from the exterior unless to one conversant with the prescribed combination and manipulation of my plural push button mechanism, it may be quickly and conveniently unlocked or relocked from the 25 interior without disturbing the set of the unlocking mechanism operatable only from the exterior of the door.

The controlling element in said keyless lock mechanism is the rotatable test guard cylinder G , which is loosely mounted on a horizontal shaft or spindle E , the extremities of which rest in and are supported upon recessed bracket bearings c^5 , c^6 , formed for the purpose, one, c^5 , on the end plate c^2 , 30 and the other, c^6 , on the front plate C , as will be understood by reference more particularly to Figs. 2 and 6, of the drawings. The recesses in said bracket bearings c^5 , c^6 , 35 are open at top, so that, upon occasion, as when setting or re-setting the operative combination, both the spindle E , and the test guard cylinder G , may be removed from and reinstated in the casing when the top plate is removed temporarily for the purpose.

The peripheral surface of the guard cylinder G , is shown as extended on the flat in Fig. 11, of the drawings, to facilitate an understanding of its structure and functions, by reference to which figure taken in conjunction with Fig. 8, it will be seen that the said cylinder is formed with a series of parallel longitudinal flanges g , g , the adjacent members of which form grooves between their opposed edges for the retentive support of the flanged bases of cover slides k , k , which are utilized for the purpose of preventing the entrance of the inner ends p , of the push button rods into any of the test holes g' , thus protected,—

said test holes g' , being arranged in series between the longitudinal flanges g , g . Thus by way of exemplification, said Fig. 11, shows hole No. 1, in the first row of test holes g' , as covered; hole 3 in the second row thus covered, and also hole 5 in the third row,—the combination selected and thus set being for 1, 3 and 5; and it being understood, of course, that any other plural selection of numbers might be resorted to 70 within the limit and capacity of the cylinder G , which in the present case would be a maximum of seven numbers, i. e. from 0 to 6, which is ample for all practical purposes of ordinary use, although a greater or less number of rows of test holes may be provided within the scope and intention of my invention in this particular, which contemplates broadly any plurality of rows of test holes g' , g' , according to special requirements of use. 75

As a matter of convenience, the test holes g' , g' , and the rows thereof, are numbered consecutively for convenience in effecting a 80 desired operative combination.

A coiled spring j , connects one end of the test guard cylinder G , with the spindle E , and tends constantly to cause an arm g^2 , on the other end of said cylinder to contact with a stop c^7 , on the back plate C' , of the 85 casing, as shown in Fig. 4, of the drawings, thereby prescribing the normal position of said cylinder.

A ratchet wheel m is rigidly attached to the extremity of the test guard cylinder G , 100 adjacent to the coiled spring j , and engaging therewith is a pawl m' , pivotally mounted upon and between suspender bearings c^8 , c^8 , on the under side of the cover plate C' .

Positioned within the test guard cylinder G , and rigidly attached to the spindle E , 105 is a counterweight W , extending longitudinally for the full length of the rows of test holes g' , as shown more particularly in Fig. 6, of the drawings; and also rigidly attached to said spindle E , but exterior to the test guard cylinder G , is a circuit closure arm e , 110 for contactual engagement with the terminals a , a , of an electric circuit a' , a' , in which is interposed an electric bell or equivalent alarm device A , as indicated in Fig. 6, of the drawings. The upper portion of the counterweight W , constitutes a full length trip arm or rocker w . Hence in the event of an inner end p , of one of the push button rods P , protruding through an unprotected test hole g' , in the cylinder G , as shown in Fig. 8, the spindle E , will be rotated in part and sufficiently to cause the circuit closure 115 are e , to contact with the terminals a , a , and sound an alarm. Upon the release and automatic retraction of the push button rod P , involved in this action, the counterweight W , will insure the return of the spindle to 120 normal position. 125

As will be seen by reference more particularly to Figs. 12 and 13, of the drawings, each push button rod P , is supported in bearings in the rear of the recessed door

- 5 plate d , in which the enumerated buttons p' , are located and displayed, and also on the base plate C' , and are each provided with a shoulder p^2 , which rest normally against said base plate C' , being held thereagainst 10 by the upper bifurcated end of a retractile leaf spring q , attached at their lower extremities to said base plate C' .

In order to prevent the inward projection of more than one push button rod P , at a 15 time, each leaf spring q , is provided with a feeler pin q' , the end of which is in alignment with a longitudinal slot r , formed by and between the anti-friction roller channel r' , and its cover plate r^2 , said channel r' , being formed in the upper portion of a 20 bracket R , secured to the base plate C' , and extending the full length of the row of push button rods as shown more particularly in Figs. 3, 9 and 10, of the drawings. The 25 channel r' , is filled with anti-friction rollers r^x , except that sufficient looseness and play is provided therebetween for the interposition of a single feeler pin q' , between adjoining rollers as indicated at the right hand end of the channel r' , in said Fig. 3,— 30 this intrusion insuring the close contact of the other rollers with each other and with the ends of the channel until the feeler pin q , is withdrawn.

35 Thus, obviously, while one feeler pin q' , is within the channel r' , it will prevent the intrusion of others, so that two or more push button rods cannot be operated simultaneously.

40 A trip arm g^4 , for engagement with the upper end of the spring latch lever L , is mounted adjustably upon the test guard cylinder G . That is to say, said trip arm g^4 , 45 may be moved and set as related to the particular row of test holes g' , in which a cover slide k , is positioned to close the hole corresponding to the last number in the combination for which the cylinder is set, as for 50 instance hole 5 in the third row, as provided for the combination illustrated in Fig. 11, so that upon the engaging of the end p , of the proper push button rod P , with said cover slide k , and the consequent partial rotation of the cylinder G , the trip arm g^4 , 55 will contact with the latch lever L , and rock it over against the resistance of the spring l' , as shown in Fig. 5, sufficiently to release the detent arm h^4 , and permit the retraction of the bolt B , by means of the thrust arm h , on the handle spindle H .

60 As shown more particularly in Fig. 14, of the drawings, this adjustment of the trip arm g^4 , is provided for by mounting it on a ring g^5 , positioned on the cylinder G , over

an annular groove g^6 , in the periphery thereof, the set screw g^7 , binding against the bottom of the groove, to secure the parts in desired position.

Upon the retraction of the bolt B , as 70 above set forth, the inclined plane b' , provided for the purpose on the upper side thereof, will raise a rod m^2 , connected with the pawl m' , sufficiently to release the latter 75 from the ratchet wheel m , and thereby allow the spring j , to return the cylinder G , to normal position with its arm g^2 , resting against the stop c^7 .

Not only the numbers constituting the operative combination must be known, but 80 their sequence also, in order to successfully manipulate the cylinder G , to release the bolt B , when thrust outward as in Fig. 2. Thus by way of example, and referring again to the combination 1, 3 and 5 illustrated in Fig. 11, of the drawings, the pressing inward of push button designated 85 1 acting against the slide k , covering the test hole 1 in the first row on the periphery of the cylinder G , will cause the latter to 90 advance from normal a distance equal to the space between adjoining rows, or from row 1 to row 2, the pawl m' , admitting this degree of movement but preventing retraction. Then if button 3 be next pressed inward 95 it will encounter the slide k , covering the hole 3, in row 2, of the cylinder, thereby bringing row 3 into position, so that the subsequent action of press button 5 will result in contact with the slide k , covering the 100 hole 5, in said row 3, thus causing the trip arm g^4 , to rock the level L , and release the bolt B . Should any press button other than 3 be pressed inward after the initial movement of push button 1, the inner end of the 105 push button rod will enter an uncovered hole g' , in the periphery of the cylinder G , resulting in the rocking of the counterweight W , and the sounding of an alarm 110 as hereinbefore set forth, and also, by reason of the rigid connection between said counterweight W , and the spindle E , causing the arm e^1 , thereof, acting through the medium of the connection e^2 , to raise the pawl m' , from the ratchet m , so that the 115 coiled spring j , can return the cylinder G , to its original position, with its arm g^2 , resting against the stop c^7 .

What I claim as my invention and desire to secure by Letters Patent, is:— 120

1. In locking mechanism of the character designated, the combination of a plurality of push button rods, means for effecting their automatic retraction, a test guard cylinder formed with parallel rows of test 125 holes and rotatably mounted on a spindle, said spindle loosely mounted on stationary bearings, cover slides mounted upon the periphery of said cylinder, a trip arm on said cylinder, a latch lever engaging with 130

a detent arm and adapted to be actuated by said trip arm, said detent arm, a bolt thrust arm on the handle spindle, and a bolt controlled thereby, substantially in the manner and for the purpose set forth.

2. In locking mechanism of the character designated, the combination of a plurality of push button rods, means for effecting their automatic retraction, a test guard cylinder formed with parallel rows of test holes and rotatably mounted on a spindle, said spindle loosely mounted on stationary open recess bearings, cover slides mounted upon the periphery of said cylinder, a trip arm on said cylinder, a latch lever engaging with a detent arm and adapted to be actuated by said trip arm, said detent arm, a bolt thrust arm on the handle spindle, and a bolt controlled thereby, substantially in the manner and for the purpose set forth.

3. In locking mechanism of the character designated, the combination of a plurality of push button rods, means for effecting their automatic retraction, a test guard cylinder formed with parallel rows of test holes and rotatably mounted on a spindle, said spindle loosely mounted on stationary bearings, cover slides mounted upon the periphery of said cylinder, a trip arm on said cylinder, a latch lever engaging with a detent arm and adapted to be actuated by said trip arm, said detent arm, a bolt thrust arm on the handle spindle, and a bolt controlled thereby, together with a spring connection interposed between said cylinder and its supporting spindle, and an arm on said cylinder adapted to contact with a stop prescribing the normal position of said cylinder, substantially in the manner and for the purpose set forth.

4. In locking mechanism of the character designated, the combination of a plurality of push button rods, means for effecting their automatic retraction, a test guard cylinder formed with parallel rows of test holes and rotatably mounted on a spindle, said spindle loosely mounted on stationary bearings, cover slides mounted upon the periphery of said cylinder, a trip arm on said cylinder, a latch lever engaging with a detent arm and adapted to be actuated by said trip arm, said detent arm, a bolt thrust arm on the handle spindle, and a bolt controlled thereby, together with a spring connection interposed between said cylinder and its supporting spindle, an arm on said cylinder adapted to contact with a stop prescribing the normal position of said cylinder, a ratchet wheel on said cylinder and a pawl engaging therewith, substantially in the manner and for the purpose set forth.

5. In locking mechanism of the character designated, the combination of a plurality

of push button rods, means for effecting their automatic retraction, a test guard cylinder formed with parallel rows of test holes and rotatably mounted on a spindle, said spindle loosely mounted on stationary bearings, cover slides mounted upon the periphery of said cylinder, a trip arm on said cylinder, a latch lever engaging with a detent arm and adapted to be actuated by said trip arm, said detent arm, a bolt thrust arm on the handle spindle, and a bolt controlled thereby, together with a spring connection interposed between said cylinder and its supporting spindle, an arm on said cylinder adapted to contact with a stop prescribing the normal position of said cylinder, means for adjusting said contact arm with relation to the rows of test holes on the cylinder, a ratchet wheel on said cylinder and a pawl engaging therewith, substantially in the manner and for the purpose set forth.

6. In locking mechanism of the character designated, the combination of a plurality of push rods, retractile springs connected therewith, each spring formed with a feeler pin, anti-friction balls opposed to said feeler pins, a test guard cylinder formed with parallel rows of test holes and rotatably mounted on a spindle, said spindle loosely mounted on stationary bearings, cover slides mounted upon the periphery of said cylinder, a trip arm on said cylinder, a latch lever engaging with a detent arm and adapted to be actuated by said trip arm, said detent arm, a bolt thrust arm on the handle spindle and a bolt controlled thereby, substantially in the manner and for the purpose set forth.

7. In locking mechanism of the character designated, the combination of a plurality of push rods, means for effecting their automatic retraction, a test guard cylinder formed with parallel rows of test holes and rotatably mounted on a spindle, said spindle loosely mounted on stationary bearings, cover slides mounted upon the periphery of said cylinder, a ratchet wheel on said cylinder and a pawl engaging therewith, a spring connection interposed between said cylinder and its supporting spindle, an arm on said cylinder adapted to contact with a stop prescribing the normal position of said cylinder, a trip arm on said cylinder, a latch lever engaging with a spring detent arm and adapted to be actuated by said trip arm, said detent arm, a bolt thrust arm on the handle spindle, a bolt controlled thereby and formed with an inclined plane surface, and a rod connected with said pawl and bearing against said inclined plane surface on the bolt, for the purpose and substantially in the manner set forth.

8. In locking mechanism of the character designated, the combination of a plurality of push button rods, means for effecting

- their automatic retraction, a test guard cylinder formed with parallel rows of test holes and rotatably mounted on a spindle, said spindle loosely mounted on stationary 5 bearings, cover slides mounted upon the periphery of said cylinder, a counterweight positioned within the cylinder and rigidly attached to said spindle, and an arm rigidly attached to said spindle external to the cylinder, for the purpose and substantially in the manner set forth.
9. In locking mechanism of the character designated, the combination of a plurality of push rods, means for effecting their automatic retraction, a test guard cylinder formed with parallel rows of test holes and rotatably mounted on a spindle, said spindle loosely mounted on stationary bearings, 10 cover slides mounted upon the periphery of
- said cylinder, a ratchet wheel on said cylinder and a pawl engaging therewith, a spring connection interposed between said cylinder and its supporting spindle, an arm on said cylinder adapted to contact with a stop prescribing the normal position of said cylinder, a trip arm on said cylinder, a latch lever engaging with a spring detent arm and adapted to be actuated by said trip arm, said detent arm, a bolt thrust arm on the handle spindle, a bolt controlled thereby and 15 formed with an inclined plane surface, and a rod connected with said pawl and bearing against said inclined plane surface on the bolt, together with independent means for releasing said spring latch lever, for the purpose and substantially in the manner set forth.

LOUIS SOLOMON.
